CORE BINDER MATERIAL

Arthur W. Goos, Marquette, Mich., assignor to
 Cliffs Dow Chemical Company, Marquette,
 Mich., a corporation of Michigan

No Drawing. Application July 2, 1937,
 Serial No. 151,661

1 Claim. (Cl. 22—188)

This invention relates to an improved core binder for use in making foundry castings and the like, and to a material for this purpose derived from the pyroligneous liquor obtained in 5 the destructive distillation and carbonization of wood.

In the destructive distillation or carbonization of wood there are originally volatilized many substances which, when subsequently condensed, are 10 found to be incapable of revolatilization. Other substances are present which although volatile under some conditions are not volatile in the presence of water. These materials are found in the "soluble tars" and a portion of the "in- 15 soluble" or "settled tars". The expression "soluble tars", otherwise called "dissolved tars", is defined here as that portion of the pyroligneous liquor obtained in the process of wood carbonization which remains as a substantially water- 20 soluble residue after substantially all of the insoluble or settled tar has been removed, and after the "methanol products", (including acetone, methyl acetate, etc.), acids of the acetic acid series, wood oils, and other compounds azeo- 25 tropic with water, and most of the water have been substantially removed therefrom by distillation and/or evaporation. Depending upon the method employed in its isolation, soluble tar may 30 accompany other tarry residues so that when the mixture is isolated it is only partially water-soluble. In such cases the water-soluble portion will 35 contain the soluble tar. The expressions "soluble" and "insoluble", employed in connection with the tar fractions, refer to the solubility of these materials in water. I have found that soluble tars can be obtained in a variety of ways 40 depending on the refining processes employed in producing recognized useful products from the pyroligneous liquor. Regardless of the refining method employed these tars are invariably present. It has long been the practice of wood distillers to consider residues containing the soluble tars as waste products and in spite of their low 45 calorific values, these have ordinarily been burned or otherwise destroyed.

A wide variety of substances have been proposed and employed as binding materials for foundry sands or the equivalent of such sands in the preparation of cores for use in foundry castings. Many of these substances have been edible products such as molasses, dextrines, flour, etc.

I have now found that the soluble tars obtained by certain preferred processes from the pyroligneous liquors in wood carbonization processes are especially desirable as core binding ma-

terials. The soluble tars, being inedible products, may readily replace and make available for employment in food products those edible materials heretofore employed as core binders. I have found further that the soluble tars derived from any type of wood ordinarily subjected to carbonization may be employed for this purpose regardless of the method by which the wood is carbonized or treated. Several processes are employed in the wood distillation and carbonization industry which result in the formation of soluble tars which can be isolated by the methods outlined briefly in the following paragraphs.

The water-soluble portions of the material precipitated electrostatically, or by any other partial condensation, from the hot vapors from wood carbonization retorts prior to condensation of substantial quantities of water therefrom, contain substantial amounts of soluble tar which is 10 useful as a core binding agent.

In carrying out the so-called calcium acetate process, the pyroligneous liquor may be substantially freed from insoluble tars, suitably by decantation, prior to the evaporation from such liquor of the methanol products and the acid 15 products. Occasionally, however, the insoluble tar is left in the liquor. The methanol products, i. e. methanol, acetone, methyl acetate, etc., may be removed from the liquor prior to the acid 20 evaporation step or they may be distilled concurrently with the acid portions. In any case, the water-soluble portion of the material remaining as a residue, or tar, after the point in 25 the process at which the acids have been removed by distillation or evaporation, is useful 30 as a core binder.

The pyroligneous liquor from wood carbonization may be separated from insoluble tar, esterified, and the volatile products including methyl 35 acetate removed by distillation. The aqueous residue contains soluble tar.

Some processes for the recovery from the pyroligneous liquors of acids of the acetic acid series involve an extraction of such acids from the pyroligneous material. This extraction is ordinarily carried out after separation of the insoluble or settled tar since this type of material, while insoluble in water, is soluble in most of the extractants employed and would constitute an undesirable impurity in the acid extracts. The 45 extraction of the acid portion of the pyroligneous liquor may be carried out in any one of several methods, of which the following are probably the most satisfactory. In one process the pyroligneous liquor is first de-methanolized and then 50

extracted with a solvent for acetic acid. The aqueous residue from this process contains soluble tar. In another method, after the pyroligneous liquor has been de-methanolized, the remaining solution is subjected to evaporation or distillation whereby acids and other volatile products are removed. Most of the soluble tar from the pyroligneous liquor will remain in the residues at this point. The distillate may then be extracted to remove acids and, on occasion, soluble tar will be found in the residue. As an alternative procedure the insoluble tar may be removed from "green" pyroligneous liquor which is then subjected to extraction. The residue from the extraction, after a subsequent concentration by evaporation or similar procedure, contains soluble tar which is satisfactory for use as a core binder.

Many of the processes for the recovery of valuable products from pyroligneous liquors involve evaporation or distillation of the methanol products followed by an azeotropic distillation of water with certain inert recoverable and ordinarily water-immiscible solvents such as ethers, esters, or certain wood oil fractions. Such a process may consist of the following steps: The pyroligneous liquor is de-methanolized and separated from the settled or insoluble tar. The aqueous portion is then subjected to evaporation or distillation and the aqueous residue contains soluble tar satisfactory for use as a core binder. The material which distilled in the evaporation step is subjected to azeotropic distillation; water and ethyl ether or the like passes off as an azeotropic mixture while the residue from this distillation contains substantially dehydrated acetic acid and a relatively small quantity of a soluble tar.

In all of the usual methods employed in the recovery of what are ordinarily considered to be valuable products from pyroligneous liquor, a satisfactory water-soluble core binding material remains in the aqueous residues from evaporation and/or distillation. Any such residues which, on evaporation, with or without previous separation of insoluble or settled tars, results in a tarry residue from which can be isolated a substantially water-soluble product of syrupy consistency, and which exhibits a cohesive effect on core-making materials when mixed therewith and heated, is satisfactory for our purpose.

Although materials containing both soluble and insoluble tars may be employed quite satisfactorily as core binders, I prefer to employ those residues which are substantially free from the insoluble substances, since these latter materials do not contribute materially to the binding characteristics of the soluble tars, and further, because the insoluble materials are highly colored, somewhat toxic substances, have an offensive odor, and are therefore unpleasant to handle. I have found a variety of methods whereby insoluble portions may be removed from the soluble tars obtained from pyroligneous acid leaving the most satisfactory type of binder. Such processes may involve filtration, decantation, centrifugal separation, neutralization, and/or extraction.

I have employed my new core binding material in the preparation of sand cores for use in casting gray iron and other ferrous metals as well

as in the casting of magnesium and similar readily oxidizable metals and their alloys. Water-soluble tars contribute the desired binding characteristics to a sand core, making possible the preparation of clean castings substantially free from adhering particles of sand.

My new binding material may be used for making foundry cores in the usual manner by mixing the same with sand or other core-making material and with water in correct proportions. The resulting mixture can be formed into cores, molds, or portions of molds and baked in the usual manner, forming hard cores or molds which can be handled and used in the usual way in making castings. The proportion of binder, water, and sand, or its equivalent, will vary depending on the kind and fineness of the sand and on the desired core characteristics. It may, on occasion, be desirable to incorporate in the core composition small amounts of other core-binding agents to accomplish some special purpose, but I have not found this step to be necessary in any of my work. As an example of one core composition which I have found to be satisfactory for many purposes, one part of water-soluble tar having a specific gravity at 20°/20° of 1.295, and containing about 35 to 40 per cent water, was mixed with 40 parts, by volume, of fine lake sand and sufficient water to give a suitable molding consistency. This material was baked for 1 hour at about 350° to 400° F. and produced a strong core which was found suitable for foundry use. This core had a hard surface and was found to retain its strength even when stored for several days in a humid atmosphere prior to use. From about 1.5 to about 5.0 per cent of core binder, based on the volume of sand, is usually sufficient.

I have found, in general, that less baking is required to produce a satisfactory core comprising water-soluble tars than with many of the core-binding agents heretofore employed. It has also been observed that considerably less gas is evolved from the core composition during baking when water-soluble tars are employed as the binder than when many other core-binding agents are employed. Good cores are produced when my new core-binding material is employed with clean sand, but I have found that the binder is especially adapted for use in foundry sands containing clay or silt. In either case, the use of water-soluble tar as a binder results not only in the production of good cores and molds after baking, but also produces a core or mold composition having good wet or "green" strength prior to baking.

Other modes of applying the principle of my invention may be employed instead of those explained, change being made as regards the materials employed, provided the ingredients stated by the following claim or the equivalent of such stated ingredients be employed.

I therefore particularly point out and distinctly claim as my invention:

As a core binder, a viscous aqueous solution of the water-soluble tars obtained from pyroligneous acid.

ARTHUR W. GOOS.
